UNITED STATES PATENT OFFICE.

RICHARD M. AHRENS, OF OAKLAND, CALIFORNIA, ASSIGNOR TO CALIFORNIA TRANSIT COMPANY, OF OAKLAND, CALIFORNIA, A CORPORATION OF CALIFORNIA.

SLIDING-WINDOW HOLDER.

Application filed October 11, 1926, Serial No. 140,760. Renewed June 1, 1928.

This invention relates to improvements in horizontal sliding windows, and particularly to windows of this character such as are mounted in motor stages and similar vehicles.

The principal object of my invention is to provide a holding means for the windows which, while allowing them to be readily moved when desired to adjust their setting, is so arranged that the windows will be normally held against movement with equal efficiency regardless of the position of the windows in their frames and without any attention on the part of the operator being necessary to thus maintain them locked against movement.

The holding means is also so arranged that both the top and bottom edges of the windows are clamped for their entire length, thereby eliminating vibration and rattles. At the same time the locking means is yieldable to a certain extent so that the windows can yield with any give of their frames, thus reducing the possibility of breakage of the windows to a minimum.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of the window structure partly broken out to show the yielding locking mechanism and looking at the inner faces of the windows.

Fig. 2 is an enlarged transverse section on the line 2—2 of Fig. 1.

Referring now more particularly to the characters of reference on the drawings, the window frame comprises side members 1 (which extend below the windows to the frame of the car or to the bottom of the door if the windows are mounted in the latter), a top member 2 and a bottom member 3. The side members above the bottom member and the top member are provided with inwardly projecting and transversely grooved felt pads 4 to form guides and cushion means for the edges of transversely spaced window panes 5 which as is custom-

ary overlap at their adjacent ends when both windows are closed, as shown in Fig. 1.

The bottom frame member 3 is provided at its upper face with a longitudinal groove 3^a in which is positioned a rigid strip 6 preferably of metal. On the upper face of this strip a grooved felt pad 7 is fixed, this pad being vertically alined with the upper pad 4 in opposed relation thereto to receive the lower edges of the panes. A plurality of longitudinally spaced bolts 8 is secured to and depend from the strip 6 through enlarged openings in the frame 3 and through guide plates 10 mounted over said openings on the lower face of the frame.

Compression springs 11 disposed about the bolts bear at their upper ends against the strip 6 and at their lower ends against the plates 10. These springs tend to force said strip upwardly and therefore clamp the panes 5 between the opposed pads 4 and 7 for their full length, thereby equalizing the clamping pressure on the panes, and also preventing the same from vibrating and rattling.

Below the frame 3 the bolts are secured to the horizontal flange 12 of an angle plate 13 which lies adjacent one face of a vertical frame structure 14 which projects below the frame 3 outwardly of the plane of the bolts 8 and is practically made as a part of said frame 3. The bolts are adjustable in the flange so that the tension of the springs can be altered at will.

Secured to the inner face of the plate centrally of the length thereof is a vertical and transverse bracket 15 onto which a lever 16 is pivoted intermediate its ends. One end of this lever projects through the plate 13 and is pivoted onto a plate 17 mounted on the structure 14. The opposite end of said lever inwardly of the window has a single pad 18 thereon. The pivotal connection of this lever with the member 14 is the sole connection of the plate with the frame structure. This permits of a limited vertical locking of the plate and the parts connected thereto so that they can follow any weaving or give of the window frame. The springs being independent can yield as required by this movement of the plate. In this manner the placing of excessive strain on the panes with such give of the frame is avoided.

When the pad 18 is depressed the plate 13 is lowered and the strip 6 is of course

lowered also so that the opposed horizontal edges of the panes are unclamped and may be slid freely along the guide pads. Upon releasing the lever the springs again exert their pressure against the strip 6 to force the adjacent guide pad into clamping engagement with the adjacent edges of the windows.

When the structure is installed in a car 10 the plate 13 and the adjacent portions of the bolts 8 are concealed from view by a finish panel 19 or the like which depends from the member 3 inwardly of the plate 13, the lever 16 projecting through a vertical slot in said 15 panel.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the 25 invention, as defined by the appended claims.

Having thus described my invention what I claim as new and useful and desire to secure by Letters Patent is:

1. A sliding window holder comprising a 30 frame structure to receive a pane for horizontal sliding movement, guides for the horizontal edges of the pane, a rigid strip mounted in the frame extending lengthwise of and on which one of said guides is mounted, said strip being movable to and from the adjacent edge of the pane, yieldable means applied to the strip at different points in its length and acting automatically and independently to force the strip toward the 35 pane, and a control member applied to the strip for moving the same away from the pane.

2. A sliding window holder comprising a 40 frame structure to receive a pane for horizontal sliding movement, guides for the horizontal edges of the pane, a rigid strip mounted in the frame extending lengthwise of and on which one of said guides is mounted, said strip being movable to and from the adjacent edge of the pane, a plate mounted 45 in vertical alinement with and in spaced

relation to the strip, connection means between the strip and plate, springs between the frame and strip acting to force the latter toward the pane, and hand means applied to the plate to move said plate and the strip against the pressure of the springs and away from the pane.

3. A sliding window holder comprising a 50 frame structure to receive a pane for horizontal sliding movement, guides for the horizontal edges of the pane, a rigid strip mounted in the frame extending lengthwise of and on which one of said guides is mounted, said strip being movable to and from the adjacent edge of the pane, a plate mounted in vertical alinement with and in spaced 55 relation to the strip, longitudinally spaced bolts between the strip and plate, springs between the frame and strip acting to force the latter toward the pane, and a handle lever pivoted intermediate its ends onto the plate centrally of its length and onto the frame structure.

4. A sliding window holder comprising a 60 frame structure to receive a pane for horizontal sliding movement, guides for the horizontal edges of the pane, a rigid strip mounted in the frame extending lengthwise of and on which one of said guides is mounted, said strip being movable to and from the adjacent edge of the pane, a plate mounted in vertical alinement with and in spaced 65 relation to the strip, rigid connection means between the plate and strip, compression springs at spaced intervals between the frame and strip, and means for moving the plate against the pressure of the springs 70 connected to the frame structure and to the plate centrally of its length.

5. A sliding window holder including a 75 frame structure to slidably receive a pane, a guide for one longitudinal movable edge of the pane, yieldable means applied to the guide at different points in its length for 80 pressing the same against the said edge of the pane, and control means applied to said guide for withdrawing the same from engagement with the edge of the pane.

In testimony whereof I affix my signature.

RICHARD M. AHRENS
